UNITED STATES PATENT OFFICE.

ERNEST ALBERT CRIDLAND, OF LEICESTER, ENGLAND, ASSIGNOR TO UNITED SHOE MACHINERY COMPANY, OF PATERSON, NEW JERSEY, A CORPORATION OF NEW JERSEY.

WORK-SUPPORT.

1,130,801.

Specification of Letters Patent. Patented Mar. 9, 1915.

Application filed October 10, 1910. Serial No. 586,249.

To all whom it may concern:

Be it known that I, ERNEST A. CRIDLAND, a subject of the King of England, residing at Leicester, Leicestershire, England, have 5 invented certain Improvements in Work-Supports, of which the following description, in connection with the accompanying drawings, is a specification, like reference characters on the drawings indicating like 10 parts in the several figures.

This invention relates to machines for making turn shoes and relates particularly to devices to assist in performing thereon the operation known as "re-forming".

15 In the operation of re-forming a turn shoe, it has been found necessary, after the shoe has been stretched on the expanding jack of the re-forming machine, for the operator to use a hammer or jiggering tool to 20 smooth out the upper leather adjacent to the feather of the insole at the toe, and along the sides of the shoe and occasionally at the heel seat.

In prior machines it has been customary 25 to so construct the jack that the sole of the shoe, when arranged thereon is disposed in approximately a horizontal plane. In this position of the shoe, however, it is difficult for the operator to hammer, tap up or beat 30 out those portions of the shoe upon which this operation is necessary or desirable.

It is an object of the present invention to overcome this difficulty and inconvenience and to this end the invention comprises an 35 expansible jack for re-forming turn shoes in which the shoe is supported with its sole at a convenient angle to the horizontal.

The shoe is inclined so that its sole is at approximately an angle of 45° with the 40 horizontal as it has been found that this inclination is most suitable and convenient for the operator when he is performing the operation of re-forming the sole or tapping up the upper at the feather.

45 To further facilitate operations upon the shoe the portion of the jack carrying the shoe is arranged to rotate about the longitudinal axis of the inclined portion of the jack and the inclined portion is arranged to revolve about a vertical axis. The toe, the sides or the heel end of the shoe may thus be brought to that position which is found most suitable for the convenience of the operator.

Another feature of the invention is an expandible jack embodying mechanism for use in jacks for general purposes but which is especially designed for use with the other features of this invention in re-forming turn shoes. The expandible jack is supported so 55 that it may not only be rotated as above stated, but so that the expansive and contractile movements of the jack are entirely independent of this rotary movement and preferably the mechanism is so arranged 60 that these movements are effected alternately by power means. By this construction the jack may be rotated in either its expanded or contracted position or during 65 the transition from either position to the other. This construction is also adapted to the vertical form of jack.

These and other features of the invention will appear more fully from the following 70 description when read in connection with 75 the accompanying drawings, and will be pointed out in the claims.

In the drawings:—Figure 1 shows a side view, partly in section, of a turn shoe re-forming jack embodying the present invention; Fig. 2 is a front view of the lower portion of the machine shown in Fig. 1; Fig. 3 is a transverse section on the line 3—3 of Fig. 1; Fig. 4 is a detail, partly in section, to be subsequently referred to.

85 The base of the preferred expanding form of jack comprises a vertical standard or column 1 to which is secured the upper inclined portion or head 2. This portion is arranged for limited rotatory adjustment about a vertical axis and longitudinally thereof and may be clamped in position in the top of the standard 1 which is slotted and provided with ears 3 on opposite sides of the slit and the bolt 4 extending through the ears and adapted when tightened to spring the upper portion sufficiently to grip the trunnion 5 of the inclined portion 2.

90 The top of the inclined head is provided with a circular top plate 6 upon which rests the jack supporting casing 7. This casing 95 is provided with a flange 8 depending from its lower periphery, the flange being provided with a groove 9 just below the top plate 6 in which is set a ring 10 which 100 engages the lower surface of the top plate 6 near its edge. Provision is thus made for rotation of the casing 7 about the longitudinal axis.

dinal axis of the inclined head 2. The bar 11 is guided for longitudinal movement along the axis of the inclined head 2; at its lower end it is provided with a rack 12 and 5 at its upper end with a socket in which a projection 13 on the lower end of the double rack bar 14 is pivotally disposed; the projection 13 is provided with a groove and a pin 16 passes through the socket and groove 10 whereby the projection is retained in the socket but pivotal movement between the bar 11 and double rack bar 14 is permitted.

Suitably journaled in the casing 7 are two pinions 17, 18. These are provided with 15 teeth only for a portion of their length and for a portion of their circumference; upon each beyond the teeth at one end is the diminished portion 19 journaled in the openings 20, beyond the teeth at the other end 20 is a cylindrical portion 21 of the same diameter as the toothed portion and each is provided with a groove 22 into which a screw 23 extends for retaining the pinion against longitudinal movement. Beneath the pinion 17 is the rack bar 24 from 25 one end of which rises the standard 25 for supporting the heel portion of the expandible last. Beneath the pinion 18 is the rack bar 26 from one end of which rises the 30 standard 27 for supporting the toe portion of the expandible last. The double rack 14 rises between the rack bars and engages with the teeth upon its sides the pinions 17 and 18.

35 It will now be apparent that when the bar 11 is moved longitudinally upward the double rack bar 14 will be forced upward and the pinions rotated outwardly in opposite directions. The pinion 17 will thus cause 40 the rack 24 to move the heel portion of the last outward and the pinion 18 will operate the bar 26 to move the toe portion of the last outward. The toe and heel portions of the last are thus moved simultaneously outward to stretch the shoe positioned thereupon. It will be seen that by the means 45 just described the shoe may be stretched upon the last and that either before, during, or after the stretching operation it may be 50 rotated to any angular position about the axis of the inclined portion 2.

The means for operating the jack to stretch the shoe consists of a toothed segment 28 pivoted at 29 and provided with a 55 lever projection 30 which is oscillated by a connecting rod 31. The lever projection 30 of the segment 28 has apertured bifurcations 50, at its free end. A block 32 having flattened portions 51 (Fig. 4) is pivoted in 60 it the reduced portion 33 of the connecting rod 31. This reduction provides below the block 32 a shoulder 34 against which the block 32 rests and which during upward 65 movement of the connecting rod 31 com-

municates positive upward movement to the lever 30. Upon the reduced portion of the connecting rod above the block 32 is a spring 35 and upon the end of the rod is a thumb nut 36 against which the spring 70 abuts. Thus, when the connecting rod moves downwardly yielding pressure is applied to the lever 30 through the resilient means 35 and this pressure is communicated as described to the heel and toe portions of the 75 expandible last to stretch the shoe thereupon.

Motion is given to the connecting rod 31 by the crank 37 upon the shaft 38 which is journaled in the boxes 39, 40 on the main 80 frame of the machine. The pitman bearing 41 on the wrist pin of the crank is provided with a neck 42 into a threaded hole in which one end of the connecting rod 31 is screwed and wherein it may be secured in 85 any position of longitudinal adjustment by the lock nut 43. Provision is thus made for adjusting the shoulder 34 relatively to the crank to regulate the position of the heel and toe parts of the expandible jack when 90 closed. The pulley 44 is constantly driven from any convenient source of power and by means of an intermittent clutch, motion is communicated therefrom to the shaft 38 for periods of a half-revolution at a time. 95 When the clutch is thrown in by the lever 45 the shaft 38 makes one half a revolution and stops, preferably upon a "dead center" in each position. The clutch except in combination with other elements of the machine 100 forms no part of my invention, clutches for performing this function being well known in the art.

In the operation of the machine the operator manipulates the clutch lever to bring 105 the wrist pin of the crank 37 into its uppermost position and to thus bring the heel and toe portions of the last nearest together or to closed position by the engagement of the shoulder 34 with the lever 30 and its consequent upward movement. When the last is in this position the turn shoe may be readily placed thereupon and the operator then by moving the clutch lever 45 in the opposite direction causes the crank to make another half-revolution, to the position shown 110 in Fig. 1. In this movement the downward motion of the connecting rod 31 is communicated through the spring 35 to the lever 30 and segment 28, to the bar 11, double rack 120 bar 14, pinions 17 and 18, racks 24, 26 respectively and the attached standards 25, 27 which are thus moved outwardly to separate the heel and toe portions of the expandible last and stretch the shoe placed 125 thereon.

During this movement the spring 35 will be compressed and the stretching tension to which the shoe is thereby subjected will depend upon the amount of compression of 130

- the spring which may be regulated to the amount desired by adjusting the thumb nut 36 upon the reduced portion 33 of the connecting rod. The expansive movements of 5 the last may be repeated at will and the turn shoe thus thoroughly stretched and formed, the manipulation of the sole and shoe by the hand tool being interspersed between the stretching operations of the expanding last.
- 10 Having thus described the preferred embodiment of my invention, which may however be variously modified, and explained the operation thereof, I claim as new and desire to secure by Letters Patent of the
- 15 United States:—
1. A machine for reforming turn shoes comprising a standard having a portion arranged at a fixed acute angle to the vertical, an expansible last mounted on said standard,
  - 20 power operated mechanism for repeatedly and forcibly expanding the last while it is within the shoe, and means for controlling the number of power operations to which the shoe is subjected.
  - 25 2. In a device of the class described a standard, a head extending therefrom at a permanent angle of substantially 45° to the horizontal, a last support arranged on said head to rotate about an axis inclined at said
  - 30 angle, and means comprising a depending flange on the last support and a coöperating ring thereon and engaging the head for holding the last support upon the head.
  - 35 3. A device of the character described comprising an upright column, an inclined head mounted for adjustment axially of said column in the top thereof, an expansible last mounted on said head for rotation with respect thereto, and means for expanding said last.
  - 40 4. In a device of the class described, the combination with an upright standard, of an inclined head mounted thereon, an expansible last comprising toe and heel portions 45 rotatably mounted on said head, and means for moving the toe and heel parts of the last toward and from each other independent of the rotative movement of the last.
  - 45 5. In a device of the class described, the combination of an expansible last having heel and toe portions, means for maintaining said last in constant angular relation to a horizontal plane, means permitting the last to be rotated about an axis 50 in the said angular relation, and power-operated means under manual control and acting independently of said rotation for resiliently moving said heel and toe portions simultaneously from each other and, upon further manipulation of said manual control, for moving them toward each other.
  - 55 6. In an expansible last, means for operating the same comprising standards for the heel and toe portions of the last, racks at an angle to the standards and connected there-

- with, pinions engaging said racks, a double rack engaging both pinions, a rack bar having swiveled connections with said double rack bar, and means to reciprocate said rack bar.
- 70 7. A device of the character described comprising, in combination, an upright support, a head portion arranged at an angle to the upright support, an expansible last rotatably carried on said head, said last having heel and toe portions, and operating means comprising racks and pinions to positively contract and yieldingly expand said heel and toe portions independently of rotary movement of the last.
- 75 8. In a device of the class described, a support, an inclined head having a circular top plate on said support, a last support mounted on said head and having a depending flange surrounding said top plate and provided with a groove, a retaining ring seated in said groove below the top plate whereby rotation of said last on said head is permitted, and means for contracting and expanding said last independently of its 80 rotating movement.
- 85 9. In a device for re-forming turn shoes, an extensible last having heel and toe parts and provided with a pivot at substantially right angles to the longitudinal medial line 90 of the last, means supporting said pivot for rotation on an axis at an acute angle to the horizontal, and means for automatically moving said heel and toe parts simultaneously from positions of contraction to positions of distention and back again.
- 95 10. In a device of the class described, a last comprising heel and toe parts, means for moving said parts simultaneously and equally from the axis of the last, said axis 100 being perpendicular to the plane of the heel plate at a fixed acute angle to the horizontal and passing through the shank, means mounting said last for rotation about said axis, means acting upon said moving means 105 to positively close said parts and to open them resiliently, and a clutch adapted, upon one actuation, to actuate said acting means to positively close the last parts and upon the next operation to open said parts resiliently and so on alternately.
- 110 11. In a device of the class described toe and heel last portions, a support therefor mounted for rotation about an axis lying between the last portions, and means movable 115 along said axis for moving said last portions relatively to said axis, and at right angles thereto.
- 115 12. In a device of the class described, a support, last portions arranged to slide on 120 said support in the direction of the longitudinal axis of the last, a mounting for said support permitting its rotation about an axis at right angles to said axis, and power means including a rack and pinion for mov-
- 125 130

ing said last portions toward and from each other simultaneously.

13. A machine of the class described having in combination a carrier 7; toe and heel members 25, 27 mounted to slide on the carrier; a support 2 on which the carrier is rotatably mounted; and mechanism comprising a non-rotatable slide 11, a joint 13, pinions 17, 18, and racks 24, 26 for communica-

cating movement to the heel and toe members while permitting the carriers to rotate.

In testimony whereof I have signed my name to this specification in the presence of two subscribing witnesses.

ERNEST ALBERT CRIDLAND.
